Primary Examiner — Charles Hanson(74) *Attorney, Agent, or Firm* — Walter Ottesen, P.A.(57) **CLAIM**

The ornamental design for an ophthalmologic cassette, as shown and described.

DESCRIPTION

FIG. 1 is a perspective view of an ophthalmologic cassette of our new design;

FIG. 2 is a top plan view of the ophthalmologic cassette of FIG. 1;

FIG. 3 is a front elevation view of the ophthalmologic cassette of FIG. 1;

FIG. 4 is a right side elevation view of the ophthalmologic cassette of FIG. 1;

FIG. 5 is an inverted rear elevation view of the ophthalmologic cassette of FIG. 1 with the top thereof facing downward;

FIG. 6 is a left side elevation view of the ophthalmologic cassette of FIG. 1; and,

FIG. 7 is a bottom plan view of the ophthalmologic cassette of FIG. 1.

The broken lines form no part of the claimed design.
